 Waugh Equipment Company, New York, N. Y.,
 a corporation of Maine

Original application March 24, 1937, Serial No.
 132,699. Divided and this application Decem-
 ber 1, 1937, Serial No. 177,456

6 Claims. (Cl. 213—46)

This invention relates to coupling and draft mechanism for use on railway vehicles, such as cars or motive power units, and is concerned more particularly with a novel apparatus for connecting together the units of a train which operates with a smooth cushioning action and reduces the transmission of shocks and jars to the car structures on which it is used. Since such shocks are more severe in buff than in draft, the new apparatus is so constructed as to have a selective or differential action, having a greater travel in buff than in draft. The mechanism of the invention may be employed with suitable changes on vehicles of various types, capacities, and sizes, but as it may be used to especial advantage on freight cars, an embodiment for that use will be described in detail for purposes of explanation.

The apparatus of the invention comprises a main cushioning device lying in a draft pocket on the vehicle and connected by a yoke to the shank of the coupler, the device engaging abutment means in the pocket. A supplemental or auxiliary cushioning unit, coming into action only under buff, lies to the rear of the main device and may conveniently be mounted behind the car body bolster. The supplemental unit is operatively connected to the main cushioning mechanism and functions in series with the main mechanism to absorb and cushion forces in buff applied to the coupler. For this purpose, an abutment means, against which the main cushioning device bears, is movable and pressure transmitting means are interposed between the abutment means and the supplemental unit. With this arrangement, the application of a force in buff to the coupler compresses the main cushioning device, or a part thereof, against the movable abutment means, and the forces are transmitted therethrough and through the transmission members to the supplemental unit. In operation under draft conditions, the movement of the coupler and yoke are resisted only by the main cushioning device which is compressed against stationary abutment means.

The cushioning device and supplemental unit may be of various constructions, but I prefer to employ a device which includes a pair of cushioning units which operate in alternation under conditions of buff and draft, with one unit free to expand as the other is compressed. Also, I prefer to employ cushioning units, both main and supplemental, which make use of rubber as the cushioning or resilient element. To this end, the units may be formed of a plurality of rubber-

bearing and separator plates of well known construction.

For a better understanding of the invention, reference may be had to the accompanying drawings, in which

Figure 1 is a longitudinal sectional view, partly in plan, showing one form of the new apparatus;

Figure 2 is a sectional view at right angles to that in Figure 1 and with parts shown in elevation;

Figures 3 and 4 are sectional views on the lines 3—3 and 4—4, respectively, of Figure 2;

Figure 5 is a view similar to Figure 1 of a modified construction;

Figure 6 is a view similar to Figure 2 of the modified construction shown in Figure 5; and

Figures 7 and 8 are sectional views on the lines 7—7 and 8—8, respectively, of Figure 6.

In the apparatus illustrated in Figure 1, the mechanism, as shown, is installed in a standard draft pocket which lies between longitudinal sills 10 of the vehicle. At the forward end of the pocket are abutment means consisting of front draft stops 11, these stops being attached to the sills in the usual manner as by rivets. The coupler 12 of the vehicle is provided with a shank 13 extending into the space between the sills, and the shank is connected by a key 14 to the arms 15 of a vertical yoke 16.

Mounted within the yoke are front and rear cushioning units 17, 18, respectively, each unit consisting of alternately arranged rubber-bearing plates 19 and plain separator plates. The plates 19 are provided with masses 20 of rubber on opposite faces thereof held in position by tongues 21 passing through openings in the plates. The units bear at their adjacent ends against opposite faces of a cross-bar 22 formed as an integral part of the yoke 16, and at their remote ends, the units bear against front and rear follower blocks 23, 24, respectively. In the normal condition of the unit, the front follower block is in contact with the front draft stops 11, and the rear follower block 24 is in contact with a rear abutment member taking the form of a yoke block 25.

The block 25 has a pair of legs straddling the rear end of the yoke and the body of the block is spaced from the rear end of the yoke a substantial distance. The rear end of the block is recessed to receive the end of a compression member 26 which extends inward past the car body bolster 27 through the center filler casting 21a, and at its rear end carries a block 28 engaging the front follower 29 of a supplemental cushion-

ing unit 30. This unit preferably consists of rubber-bearing and separator plates lying in alternation between the front follower block and a rear follower block 31, which engages stops 32 attached to the sills 15. The compression member 26 is diametrically slotted as at 33 for the passage of the king pin 34.

The yoke is supported by a carry iron 35 secured to the sills 10, and a similar support 36 is provided for the rear cushioning unit. Spacer bars 37, mounted in the space between the sills above the supplemental unit, may also be used, if desired, these bars holding the plates of the unit against vertical movement.

15 In the installation of the device illustrated, the cushioning units are under substantial initial compression, the front unit 17 being confined by the cross-bar 22 of the yoke and the follower block 23, which engages the front abutment means in the form of the draft stop 11. The rear unit 18 is confined between the cross-bar and the follower block 24, which engages the rear abutment means in the form of the yoke block 25. The block is held in position by the compression member 26, which is in turn in engagement with the front follower block 20 of the supplemental unit. The rear abutment means is, therefore, movable, and upon application of a force in buff to the coupler, the 20 rear unit 18 and the supplemental unit 30 act in series to resist the inward movement of the coupler and yoke. Upon the application of a force in draft, the forward movement of the yoke is resisted by the front unit 17 only.

35 Preferably, in the installation of the device, the several cushioning units are installed under such initial compression that each of the units 17, 18 has a capacity for expansion at least as great as the amplitude of movement of the yoke 40 when the latter is subjected to forces in buff and draft of the magnitude that occur under normal operating conditions. When the units are thus installed, one expands as the other is compressed, and the units thus make substantially continuous contact throughout normal operation, with the yoke cross-bar at one end and the follower block at the other. Accordingly, in normal operation, no spaces occur in the mechanism between the yoke and parts, such as the front draft stops, which are fast to the car structure, and the development of free slack in the connecting mechanism is thus prevented. Movements of the coupler and yoke in either 45 direction are continuously resisted by at least one cushioning unit, and as there is no free slack and no uncushioned movements, the car structure is not subjected to shocks and jars.

In the construction shown in Figure 5, the sills 38 are provided with front draft stops 39 against which bear abutment plates 40, these plates being mounted to lie along the inner walls of the sills and having integral abutments 41 on their opposite faces. The yoke 42 encircles front and rear cushioning units 43, 44, 50 each lying between front and rear followers blocks 45, 46. The rear follower block of the forward unit and the front follower block of the rear unit bear against opposite faces of the abutments 41, and the end members of the yoke 55 contact with the front follower block of the front unit and the rear follower block of the rear unit. The yoke is provided with spaced arms 47, between which extends the shank 48 of the coupler 49, and the coupler shank is secured 60 to the arms by a key 50.

At their rear ends, the abutment plates 40 contact with the forward ends of compression members 51 which extend past the car body bolster 52 through the center filling casting 52a, on which they rest, and engage the front follower block 53 of a supplemental cushioning unit 54. This unit bears at its rear end against a rear follower block 55 which abuts against draft stops 56 secured to the sills 38. The yoke is supported by a carry iron 57, and angle irons 10 58 secured to the sills 38 support the abutment plates 40. If desired, wear plates 59 may be mounted against the inner walls of the sills to take the wear of the movable abutment plates. The supplemental unit is supported by a carry iron 60 and, if desired, spacer bars 61 are mounted at the upper ends of the sills to maintain the supplemental unit in proper position. The front and rear units 43, 44 and the supplemental unit 54 in the construction described are preferably 20 made up of alternately arranged rubber-bearing and separator plates, as previously described.

With the mechanism shown in Figures 5 and 6, upon the application of a force in buff to the coupler, the front unit 43 of the main mechanism and the supplemental unit are compressed in series, the compression of the supplemental unit occurring as the abutment plates 40 are moved rearward by force transmitted from the yoke through the front unit 43. In draft, the 30 abutment plates are held stationary by their engagement with the stops 39, and the rear unit 44 of the main device is compressed between the rear end of the yoke and the abutments 41. 35

In both the illustrated forms of the new mechanism, the movement of the coupler, produced by the application of a force in buff, is resisted by a pair of cushioning units operating in series, and this permits long travel with gradual force absorption. Forces in draft, which are likely to be less severe than those in buff, are cushioned by a single mechanism. With the construction shown in Figure 1, the development of free slack may be entirely prevented under normal operating conditions, since if the units are installed 45 under the proper initial compression, no spaces will develop in the connections between the coupler and the car body. With the construction shown in Figure 5, some slack may develop in the event that, after the application of a substantial force in buff to the coupler, the direction of force application is quickly changed. In the situation referred to, the coupler movement, produced by the force in draft, is uncushioned until the abutment plates return into contact 50 with the front draft stops, after which, further coupler movement is resisted by the rear cushioning unit 44. The development of slack in this mechanism does not occur, however, if, after the application of a force in draft, the direction of the applied force is quickly changed. In that case, the expanded front unit 43 will cushion the return movement of the coupler at 55 once. Accordingly, to obtain the full advantages of the invention, the construction shown in Figure 1 should be employed, but the Figure 5 construction is superior to an ordinary draft gear of the usual friction type, since, with a gear of the friction type, slack develops each time the 60 gear is compressed and regardless of the direction of the force applied.

This application is a division of my copending application, Serial No. 132,699, filed March 24, 1937.

I claim:

1. In a railway vehicle having a draft pocket, the combination of a coupler, a yoke connected to the coupler and extending into the pocket, a cushioning mechanism including a pair of cushioning units lying in line within the pocket and encircled by the yoke, abutment means, independent of the yoke, within the pocket, one end of each unit engaging the abutment means only and the other end of each unit engaging the yoke only and receiving compressive forces therefrom, a supplemental cushioning unit, said abutment means being movable toward and away from said supplemental unit, means limiting the movement of the abutment means away from the supplemental unit, and means operatively connecting the abutment means and the supplemental unit and transmitting to the latter forces in buff applied to the abutment means by the coupler through said mechanism.

2. In a railway vehicle having a draft pocket, the combination of a coupler, a yoke connected to the coupler and extending into the pocket, a cushioning mechanism including a pair of cushioning units lying in line within the pocket and encircled by the yoke, abutment means, independent of the yoke, within the pocket, one end of each unit engaging the abutment means only and the other end of each unit engaging the yoke only and receiving compressive forces therefrom, a supplemental cushioning unit, said abutment means being movable toward and away from said supplemental unit, means limiting the movement of the abutment means away from the supplemental unit, and means operatively connecting the abutment means and the supplemental unit and transmitting to the latter forces in buff applied to the abutment means by the coupler through said mechanism, said means including at least one compression member engaged by the abutment means and acting on the supplemental unit.

3. In a railway vehicle having a pair of spaced longitudinal sills providing a draft pocket between them, a bolster, a center filler casting between the sills in line with the bolster, and a king pin mounted vertically in said casting, the combination of a coupler, a yoke connected to the coupler and extending into the draft pocket, a cushioning mechanism including a pair of cushioning units lying in line within the pocket and encircled by the yoke, movable abutment means, independent of the yoke, within the pocket, one end of each unit engaging the abutment means only and the other end of each unit engaging the yoke only and receiving compressive forces therefrom, a supplemental cushioning unit, means for limiting the movement of the abutment means toward the coupler, and means extending through

said casting on either side of the king pin and engaging the abutment means at one end, said means transmitting to the supplemental unit forces in buff applied to the abutment means by the coupler through the cushioning mechanism.

4. In a railway vehicle having a draft pocket and a coupler, the combination of a pair of cushioning units lying in line within the pocket, a pair of movable abutment members lying along the walls of the pocket and having projections extending into the pocket and engaged by the adjacent ends of the units, a yoke encircling the units and connected to the coupler, the remote ends of the units engaging the yoke only, a supplemental unit, means for limiting movement of the abutment members in a direction away from the unit, and means interposed between the members and supplemental unit for transmitting compressive forces from the members to the unit.

5. In a railway vehicle having a draft pocket and a coupler, the combination of a pair of cushioning units lying in line within the pocket, a yoke member connected to the coupler and having a portion encircling said units, abutment means in the pocket, one end of each unit engaging a part of the yoke member only and each of the other ends of the units respectively engaging a part of the abutment means only, the abutment means having stationary and movable parts and the units operating in alternation under buff and draft conditions, the stationary part of the abutment means acting as a stop for causing one of the units to be compressed when the yoke member moves forward under a force in draft, a movable part of the abutment means moving rearwardly with the other unit and yoke member when the latter is subjected to a force in buff, a supplemental cushioning unit operable in buff only, and means interposed between and contacting with the movable part of the abutment means and the supplemental unit, said supplemental unit acting through the interposed means to resist rearward movement of said movable part.

6. In a railway vehicle having a draft pocket and a coupler, the combination of a pair of cushioning units lying in line within the pocket, a yoke encircling the units and connected to the coupler, the adjacent ends of the units engaging the yoke and the remote ends of the units being out of contact with the yoke, stationary abutment means engaging the remote end of one unit, movable abutment means engaging the remote end of the other unit, a supplemental cushioning unit, and means between the movable abutment means and supplemental unit for transmitting compressive forces from said abutment means to said unit.

LEVERETT M. CLARK.
